VALVE GRINDING MACHINE

Filed May 2, 1936

UNITED STATES PATENT OFFICE

2,113,387

VALVE GRINDING MACHINE

Herbert A. Silven, Worcester, Mass., assignor to
Norton Company, Worcester, Mass., a corpora-
tion of Massachusetts

Application May 2, 1936, Serial No. 77,553

13 Claims. (Cl. 51—105)

This invention relates to grinding machines, and more particularly to a semi-automatic valve grinding machine.

One object of this invention is to provide a simple thoroughly practical machine for grinding valves. Another object of this invention is to provide a valve grinding machine which is rapid in operation. Another object of this invention is to provide a semi-automatic grinding machine for automatically grinding automobile valve faces. Another object of this invention is to provide a semi-automatic grinding machine for grinding valves, in which a pair of work supporting members are arranged so that one is in a grinding position while the other slide is being loaded.

A further object of this invention is to provide a hydraulically operated semi-automatic valve grinding machine in which a dual work head is provided and arranged for semi-automatic control. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawing, in which is shown one of various possible embodiments of the mechanical features of this invention,

Fig. 1 is a fragmentary plan view of the improved valve grinding machine, having parts broken away and shown in section, to show the operating construction, combined with a hydraulic piping diagram to show the operation of the machine; and

Fig. 2 is a horizontal sectional view, on an enlarged scale, taken through the left-hand work supporting and rotating spindle, showing the chuck or collet actuating mechanism and the work ejector.

A grinding machine has been illustrated in the drawing having a base 10 which supports a transversely movable wheel slide 11. The wheel slide 11 is arranged to slide transversely relative to the base 10 on a V-way 12 and flat way 13. The wheel slide 11 supports a rotatable grinding wheel 14 mounted on the end of a rotatable wheel spindle 15 journaled in bearings (not shown) in the wheel slide 11. In order to drive the spindle, a well-known wheel driving mechanism may be employed, such as an overhead drive or a motor drive. As illustrated, the other end of the wheel spindle 15 is provided with a grooved pulley 16

which is connected by driving belts 17 with a similarly grooved pulley 18 mounted on the outer end of a motor shaft 19. An electric motor 20 carrying the motor shaft 19 is mounted on the upper portion of the wheel slide 11 and serves to rotate the wheel 14 at the desired grinding speed. The wheel slide 11 may be fed transversely in order to set up the machine or to compensate for grinding wheel wear by a manually operable feed mechanism, such as that shown in the expired U. S. Patent No. 762,838 to C. H. Norton dated June 14, 1904. The wheel slide 11 is provided with a depending half nut 21 which meshes with or engages a rotatable feed screw 22. Further details of the wheel feed mechanism have not been illustrated or described since they are not considered part of the present invention. Reference may be had to the above-mentioned patent for further details of the feed mechanism.

A longitudinally movable work supporting table 25 is slidably mounted on a V-way 26 and a flat way 27 formed on the base 10. In order to obtain a maximum production on the machine, it is desirable to provide a pair of work supporting spindles which may be arranged so that while one spindle is in a position to grind a valve, the other spindle is in an inoperative or loading position. In the preferred construction, the longitudinally movable work supporting table 25 supports a pair of transversely movable work heads 30 and 31 which are slidably mounted on ways 32 and 33 formed on the upper surface of the table 25.

The work supporting table 25 which supports the work heads 30 and 31 is arranged so that it may be moved longitudinally relative to the base 10 to facilitate simultaneously adjusting the work heads 30 and 31 relative to the grinding wheel 14. A manually operable traverse mechanism has been illustrated in the drawing comprising a manually operable rotatable hand-traverse wheel 40 240 which is mounted on the outer end of a rotatable shaft 241 journaled in the base 10 of the machine. The inner end of the shaft 241 is provided with a gear 242 which meshes with a rack bar 243 depending from the under side of the longitudinally movable work table 25. By manipulation of the hand wheel 240, the table 25 may be moved longitudinally to adjust the work heads 30 and 31 relative to the operative face of the grinding wheel 14.

A pair of cylinders 46 and 47 are fixedly mounted on the front of the longitudinally movable table 25 and serve to slidably support pistons 42 and 43 respectively. A pair of piston rods 44 and 45 are connected with pistons 42 and 43 respec-

tively. The inner ends of the piston rods 44 and 45 are connected to slides 30 and 31 respectively so that when the pistons 42 and 43 are moved within the cylinders 40 and 41 in either direction, a corresponding movement is imparted to the work slides 30 and 31 respectively.

The pistons and cylinders above described serve to cause a rapid approach of the work supporting slides 30 and 31 relative to the grinding wheel 14 or to rapidly remove the slide to an inoperative position. In order to produce a slow controlled feeding movement of the work support during the grinding operation, a feed regulating device is provided which is identical with that shown in my prior United States Patent No. 2,023,704 dated December 10, 1935 to which reference may be had for a detailed disclosure. The feed regulating device may comprise a dash pot cylinder 50 which is fixedly mounted on the end of the cylinder 40. A dash pot piston 51 is slidably supported on the piston rod 44 and is contained within the dash pot cylinder 50. The rapid approaching movement of the slide 30 continues until an adjustable sleeve 52 mounted on the end of the piston rod 44 engages the end face of the dash pot piston 51. Continued forward feeding movement of the work head 30 exhausts fluid from the dash pot chamber through a needle valve 54 at a rate controlled by the aperture of the needle valve 54. By regulating the needle valve 54, the infeeding movement of the work head may be varied as desired.

A similar feed regulator is provided for controlling the infeeding movement of the work head 31. This regulator comprises a dash pot cylinder 60 which contains a piston 61 slidably mounted on the piston rod 45 and contained within the dash pot cylinder 60. The rapid infeed of the work head 31 continues until an adjustable bushing or sleeve 62 supported on the outer end of the piston rod 45 engages the end face of the dash pot piston 61 which serves to retard the forward advance of the work head 31 as controlled by the aperture of a needle valve 64. In order to supply the necessary fluid under pressure to operate the various mechanisms of the machine, a sump or reservoir 70 is preferably located within the base of the machine. Fluid is pumped from the reservoir 70 through a pipe 71 by means of a geared pump 72 which forces fluid outwardly through a pipe 73 and through a pipe 74 and a pipe 75 to a control valve 76. Fluid under pressure from the pipe 75 enters a valve chamber 77 and passes through a passage 78 into a cylinder chamber 79 to cause a forward feeding movement of the piston 42 and the work head 30 toward the grinding wheel 14. During the forward feeding movement of the slide 30, fluid is exhausted from a cylinder chamber 80, through a passage 81, a valve chamber 82 and through a pipe 83 into the reservoir 70. The rapid infeeding movement of the slide 30 continues until the bushing or sleeve 52 engages the end of the dash pot piston 51 and thereby reduces the infeed from a rapid approaching movement to a controlled infeeding movement.

Similarly, fluid under pressure from the pump 72 passes through a pipe 94, a pipe 95, to a control valve 96 for controlling the forward and rearward feeding movement of the work head 31. Fluid under pressure passing through the pipe 95 enters a valve chamber 97 and passes through a passage 98 into a cylinder chamber 99 to move the piston 43, the work head 31, into an inoperative position so that the finish ground

work piece is withdrawn from operative engagement with the grinding wheel. During the movement of the slide 31 to an inoperative position, fluid is exhausted from a cylinder chamber 100, through a passage 101, into a valve chamber 102, and through a pipe 103, into the reservoir 70.

The valves 76 and 96 are provided with manually operable knobs 105 and 106 respectively by means of which the valves may be readily shifted so as to permit a manual control of the work heads 30 and 31 respectively, if desired.

In the preferred operation of this improved valve grinding machine, it is desirable to synchronize the feeding movements of the work heads 30 and 31 so that while one of the work heads is in a grinding position to grind a work piece, the other work head is in its inoperative or loading position. It is desirable that the movements of the two slides be automatically synchronized so that the slides will move in accordance with the desired cycle of operation. In order to accomplish this result, a main control valve 110 is provided in the fluid pressure system for automatically operating the control valves 76 and 96 in the desired sequence. The valve 110 is preferably of a piston type comprising a valve stem 112 having formed integrally therewith valve pistons 113 and 114. The valve stem 112 is provided with an operating knob or handle 111 by means of which the valve may be readily shifted from one position to the other. In the position illustrated in the drawing (Fig. 1), fluid under pressure passing through the pipe 94 passes through a pipe 115 into a valve chamber 116 and out through a pipe 117 into a valve chamber 118 to shift the valve 76 into the position illustrated in the drawing. At the same time, fluid passing out through pipe 117 passes into a valve chamber 120 at the rear of the valve 40 96 and serves to shift the control valve 96 into the position illustrated in full lines in Fig. 1, so as to cause a rearward or inoperative movement of the slide 31. During this movement of the slides 30 and 31, fluid under pressure is exhausted from valve chamber 121, through a pipe 122, into a valve chamber 123, and through a pipe 124, into the reservoir 70. At the same time, fluid under pressure is exhausted from a valve chamber 125 formed in the lower portion of the valve 96, through a pipe 126, into valve chamber 123, and also exhausts through pipe 124, into the reservoir 70.

After a work piece carried by the slide 30 has been ground to the desired and predetermined extent, the knob 111 is moved to shift the valve stem 112 into the reverse position so that fluid under pressure entering through pipe 115, into valve chamber 116, passes outwardly through pipe 122, into the valve chamber 121, to shift the control valve 76 into its reverse position. Fluid also passes through the pipe 126 into the valve chamber 125 to shift the valve 96 into its reverse position so that the work head 30 is moved rearwardly to an inoperative position while the work head 31 is moved forwardly to present a new piece of work to the grinding wheel 14 for a grinding operation.

If desired, the main control valve 110 may be automatically operated, as by means of a pair of opposed solenoids which are controlled respectively by a dwell control mechanism, such as that shown in the prior patent to Wood No. 1,969,997 dated August 14, 1934.

The work slide 30 is provided with a rotatable

work supporting spindle 150 which is rotatably supported in a bearing 151 in an upwardly extending portion 152 of the head 30. The spindle 150 is provided with a driving pulley 153 which is connected by a driving belt 154 with a pulley 155 mounted on the outer end of a motor shaft 156 which is in turn contained within an electric driving motor 157 mounted on the upper surface of the slide 30. The spindle 150 contains a collet or chuck 160 which serves as a support for a work piece, such as a valve 161. A spring 163, which is contained within the spindle 150 and is interposed between a shoulder 164 on the spindle 150 and a collar 165 mounted on the rear end of 15 the collet 160, serves to hold the collet in a clamped position to securely hold the valve 161 in operating position within the chuck.

It is desirable to provide an automatic mechanism for releasing the collet after the grinding 20 operation is completed so that the work piece, such as valve 161, may be readily removed therefrom. In the preferred construction, a fluid pressure mechanism is provided comprising a cylinder chamber 170 formed within a bracket 171. An end plate 172 fixed on the end of the collet 160 and collar 165 serves as a piston and slides within the fluid chamber 170. Fluid under pressure is admitted through a pipe 173 to move the collet 160 toward the right, as viewed in Fig. 2, against 25 the tension of the spring 163 to unclamp the work piece 161.

It is desirable that the fluid pressure admitted to the cylinder chamber 170 be controlled in timed relation with the movement of the machine parts. 30 As illustrated, a control valve 175 is mounted on the end of the table 25 and has a valve stem 176 projecting therefrom and arranged in the path of an adjustable dog 177 carried by the work head 30. Fluid under pressure from the pump 72 passes through the pipe 73, the pipe 74 and through a pipe 178 into a valve chamber 179. In the position of the valve 175, as illustrated in Fig. 1, fluid is cut off from the pipe line 173. When the work piece 161 has been ground to the 35 required extent and the slide 30 reverses and moves toward an inoperative position, the dog 177 engages the valve stem 176 and shifts the valve against a compression spring 180 so that fluid under pressure entering the valve chamber 179 passes outwardly through a pipe 181 and the pipe 173, into the chamber 170, to cause the collet 50 to move toward the right (Fig. 2) to release the valve 161.

It is also desirable to provide a suitable ejecting 55 means for rapidly ejecting the valve 161 after the collet has released the same. An ejector arm 190 is pivotally mounted on a stud 191 on the outer end of a slidably mounted rod 192. The other end of the rod 192 is provided with a piston 193 which is slidably mounted within a cylinder bore 194 within the housing 152. A spring 195 normally holds the ejector 190 and the piston 193 in their rearward position, as illustrated in Fig. 2. When fluid under pressure is admitted by the 60 valve 175, through pipe 181 and pipe 173, to release the collet, fluid under pressure also is passed through a pipe 196 to cause the piston 193 to move rapidly toward the right and thereby eject the valve 161 from the collet 160.

70 A similar work head 200 is mounted on the slide 31. This head is provided with a rotatable spindle 201 having a driving pulley 202 connected by a driving belt 203 with a pulley 204 carried by an electric motor 205. The spindle 201 carries a spring collet or chuck 206 which serves as a

support for a valve 207. A control valve 210 is carried on the end of table 25 and is provided with a valve stem 211 arranged in the path of an adjustable dog 212 carried by the slide 31. Fluid under pressure passing through the pipe 84 passes 75 through a pipe 214 into a valve chamber 215. When the slide 31 moves sufficiently in a downward direction, as viewed in Fig. 1, to shift the valve 211 into its reverse position, fluid under pressure entering the valve chamber 215 passes 80 outwardly through a pipe 216 and a pipe 217 into a chamber, corresponding to the chamber 178, to release the collet or chuck 206 and at the same time passes through a pipe 218 into a cylinder chamber which actuates an ejector 219 carried 85 by a rod 220 to eject the valve 207 from the machine.

Each of the work heads 152 and 200 is provided with an adjustable stop 220 which has either a hardened metallic or a diamond point which 90 serves to locate the face of the valves 161 and 207 in a desired and predetermined relation with the chucks 160 and 206 respectively.

In the normal operation of this machine, the valves 161 and 207 may be manually loaded into 95 the chucks 160 and 206 when the slides 30 and 31 respectively are in an inoperative position. The valves may be manually slid into place in the chucks while the chucks are continuously rotated or, if desired, the spindles may be stopped 100 during the loading period. A limit switch 230 is mounted on the end of the table 25 and is arranged in the path of an adjustable dog 231 carried by the slide 30. Similarly, a limit switch 232 is carried at the other end of the table 25 and is 105 arranged in the path of an adjustable dog 233. The limit switches 230 and 232 are normally closed limit switches and are connected in series with the electric motors 157 and 205 respectively. When the slide 30 or the slide 31 moves to an 110 inoperative position, such as slide 31 as shown in Fig. 1, the slide 31 has moved a sufficient distance so that the dog 233 engages the roller of the limit switch 232, and continued movement thereof serves to open the limit switch and break the circuit to stop the rotation of the motor 205 so that the spindle rotation will stop during the unloading and loading period.

The operation of this machine is readily apparent from the foregoing disclosure. Assuming 115 the feeding mechanisms to be previously adjusted to obtain the desired sizing of a work piece, a valve 161 has been inserted in the chuck 160 and the main control valve knob moved into the position of parts as shown in Fig. 1, which serves to 120 admit fluid under pressure through pipe 171 into valve chamber 178 to shift the valve 176 into the position as illustrated in Fig. 1 so that fluid under pressure passing through the pipe 75 into the valve chamber 179 is admitted into cylinder chamber 170 to cause an infeeding movement of the work head 30. At the same time, fluid under pressure is admitted to the valve chamber 125 179 to shift the valve 175 into the position illustrated in Fig. 1 to admit fluid under pressure to cylinder chamber 178 to move the work head 31 rearwardly to an inoperative position. The adjustable dog 212 engaging the valve stem 211 serves to operate the control valve 210 and when the work head 31 has moved through its inoperative stroke a sufficient distance to uncover the pipe 216, fluid is admitted through the pipes 217 and 218 to release the collet 206 to unclamp the work piece and to actuate the ejector 219 to rapidly eject the work piece 207 from the collet 206.

A new work piece 207 may then be inserted in the collet and held in place against an adjustable stop 220 which serves to locate the face of the valve in a predetermined relationship with the operative face of the grinding wheel 14. While the valve is placed in this position, the main control valve 111 is shifted into a reverse position which serves in the manner above described to shift the control valves 76 and 96 into their reverse position to cause the work head 30 to move to an inoperative position while the work head 31 moves the work piece 207 into an operative grinding relationship with the wheel 14.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawing is to be interpreted as illustrative and not in a limiting sense.

25 I claim:—

1. A grinding machine comprising a base, a rotatable grinding wheel, a transversely movable slide therefor, means to move said slide transversely to adjust the position of the wheel relative to the base, a pair of transversely movable work heads, a rotatable work support on each of said heads, independent feeding means to move each of said heads transversely toward and from the grinding wheel to grind a work piece to a predetermined size and to then return to an inoperative position, and means including a single control handle to control said independent feeding mechanisms so that when one of said heads is moved to grind a work piece to the predetermined size, the other head is moved to an inoperative or loading position.

2. A grinding machine comprising a base, a rotatable grinding wheel, a transversely movable slide therefor, means to adjust the position of said slide relative to the base, a pair of transversely movable work heads, an independent fluid pressure operated piston and cylinder rapidly to move each of said heads transversely toward and from the grinding wheel, an independent feed regulator for each of said heads to slow down said rapid approach to a grinding feed, and means to synchronize the movement of said pistons so that when one of said slides is moved to present a work piece for a grinding operation, the other slide is moved to an inoperative or loading position.

3. A grinding machine comprising a base, a rotatable grinding wheel, a transversely movable slide therefor, means to adjust the position of said slide relative to the base, a pair of transversely movable work heads, an independent fluid pressure operated piston and cylinder to move each of said heads transversely relative to the grinding wheel, an independent manually operable control valve for each of said cylinders, and means to synchronize the movement of said valves so that when one of said slides is moved to present a work piece for a grinding operation, the other slide is moved to an inoperative or loading position.

4. A grinding machine comprising a base, a rotatable grinding wheel, a transversely movable slide therefor, means to adjust the position of said slide relative to the base, a longitudinally movable work supporting table, means to move

said table longitudinally, a pair of transversely movable work heads on said table, an independent fluid pressure operated piston and cylinder interposed between each of said slides and the table, an independent manually operable control valve for each of said cylinders, and means to synchronize the movement of said valves so that when one of said slides is moved to present a work piece for a grinding operation, the other slide is moved to an inoperative or loading position.

5. A grinding machine comprising a base, a rotatable grinding wheel, a transversely movable slide therefor, means to move said slide transversely relative to the base, a longitudinally movable table on said base, means to traverse said table longitudinally, a pair of transversely movable work heads on said table, a rotatable work support on each of said heads, independent fluid pressure mechanisms including a piston and cylinder interposed between each of said heads and the table, a manually operable control valve, operatively connected with each of said cylinders and arranged to cause an independent movement of each of said slides towards and from the grinding wheel, and means including a main control valve which is operatively connected to actuate said valves to cause one of said work heads to move toward the operative face of the grinding wheel to grind a work piece while the other head is moved to an inoperative or loading position.

6. A grinding machine comprising a base, a rotatable grinding wheel, a transversely movable slide therefor, means to move said slide transversely, a longitudinally movable work table, a transversely movable work head on said table, a rotatable work supporting chuck on said head, means to rotate said chuck, means to actuate said chuck to clamp a work piece therein, a fluid pressure mechanism including a piston and cylinder to release said chuck, and means including a valve actuated automatically by said head when said head is moved away from the grinding wheel to admit fluid under pressure to said cylinder to unclamp said chuck and thereby release the work piece.

7. A grinding machine comprising a base, a rotatable grinding wheel, a transversely movable slide therefor, means to move said slide transversely, a longitudinally movable work table, a pair of transversely movable heads on said table, means independently to feed said heads transversely relative to said table, a rotatable work supporting chuck on each of said heads, means to independently rotate each of said chucks, means to actuate each of said chucks to clamp a work piece therein, means including a fluid pressure piston and cylinder on each of said heads to release said chuck, and independent means on each of said heads which are actuated automatically when said heads are moved away from the grinding wheel to admit fluid under pressure to unclamp said chucks and thereby release the work pieces after a predetermined grinding operation has been completed.

8. A grinding machine comprising a base, a rotatable grinding wheel, a transversely movable slide to support said wheel, means to adjust said slide transversely relative to the base, a longitudinally movable table, means to move said table longitudinally relative to the base, a transversely movable work head on said table which is arranged to move transversely toward and from the grinding wheel, a rotatable work supporting chuck on said head, means including a fluid pres-

sure piston and cylinder to cause a transverse feeding movement of said work head relative to the grinding wheel at a rapid rate, a feed regulator to slow down said rapid approach to a 5 grinding feed, a control valve arranged to control the direction of movement of said head to grind a work piece to a predetermined size, and means actuated in timed relation with the movement of said head to an inoperative position to 10 release said chuck and eject a work piece therefrom as the slide approaches an inoperative position.

9. A grinding machine comprising a base, a rotatable grinding wheel, a transversely movable slide therefor, means to move the slide transversely relative to the base, a longitudinally movable work supporting table, a pair of transversely movable work heads on said table, a rotatable work supporting chuck on each of said heads, 20 means to independently rotate each of said chucks, a spring to actuate said chuck to clamp a work piece in said chuck, means including a piston and cylinder to release said chuck, means including a fluid pressure actuated work ejector, 25 and means actuated in timed relation with the movement of said head to an inoperative position to admit fluid under pressure to unclamp said chuck and to actuate said ejector and thereby eject the ground piece of work from the chuck.

10. A grinding machine comprising a base, a rotatable grinding wheel, a transversely movable slide therefor, means to move the slide transversely relative to the base, a longitudinally movable work table, a pair of transversely movable work heads on said table, a rotatable work supporting chuck on each of said heads, a spring actuated means to operate each of said chucks to clamp a work piece in a predetermined position therein, means including a fluid pressure 40 piston and cylinder to actuate each of said chucks to release a work piece therefrom after a grinding operation, means including a fluid pressure piston and cylinder actuated work ejector, and a fluid pressure system including a control valve 45 actuated in timed relation with the movement of said heads to an inoperative position to admit fluid under pressure to the first cylinders to release said chuck and to the second cylinders to automatically eject a ground work piece from 50 said chuck.

11. A grinding machine having a base, a rotatable grinding wheel, a transversely movable slide therefor, means to move the slide transversely relative to the base, a longitudinally movable work table, a pair of transversely movable work

heads on said table, a rotatable work supporting chuck on each of said heads, a spring actuated means to clamp a work piece in said chuck, means including a fluid pressure piston and cylinder to release said chuck, means including a fluid pressure actuated piston and cylinder to eject a work piece from said chuck, means including an electric motor to drive each of said chucks, and means actuated in timed relation with the movement of said head to an inoperative position to 10 stop the rotation of the work head while in an inoperative position.

12. A grinding machine having a base, a rotatable grinding wheel, a transversely movable slide therefor, means to move said slide transversely, 15 a longitudinally movable table, a pair of transversely movable heads on said table, a rotatable work supporting chuck on each of said heads, a spring to actuate each of said chucks to clamp a work piece in each of said chucks, means including a fluid pressure operated piston and cylinder to release each of said chucks, means including a fluid pressure actuated work ejector to eject a work piece from each of said chucks, means including an electric motor on each of said heads 25 to positively rotate said chucks during a grinding operation, means to move said heads transversely relative to the grinding wheel to move a work piece into operative relation with the grinding wheel and to grind the same to a predetermined size.

13. A grinding machine having a base, a rotatable grinding wheel, a transversely movable slide therefor, means to move said slide transversely relative to the base, a longitudinally movable work table, a pair of transversely movable heads on said table, a rotatable work chuck on each of said heads, a spring to actuate said clamp to secure a work piece in each of said chucks, means including a fluid pressure piston and cylinder to 40 release said chuck after a work piece has been ground to a predetermined size, means including a fluid pressure actuated work ejector, means including an electric motor to rotate said chuck for a grinding operation, means including a control valve which is actuated in timed relation with the separating movement between the wheel and work support to admit fluid under pressure to release said chuck and to actuate said ejector, and means actuated in timed relation therewith 50 to stop the rotation of the chuck during the unloading period when the head is in an inoperative position.

HERBERT A. SILVEN.

55
